METHOD OF AND APPARATUS FOR WASH-
ING GLASSES AND THE LIKE

Vincent W. Cunningham, Chicago, Ill.

Application August 31, 1934, Serial No. 742,323

13 Claims. (Cl. 15—76)

The invention relates generally to the art of glass washing and more particularly to this art as it is concerned with the rapid commercial washing and scrubbing of glasses and similar tumblers by power means.

In such commercial glass washing operations it is customary to employ a rotary power driven scrubbing or brushing unit submerged in whole or in part in cleansing solution contained in a suitable tank or sink, the scrubbing unit usually embodying brushes for engaging both inner and outer surfaces of the glass which is held in non-rotative relation to the brushes of the rapidly rotating scrubbing unit. As a practical matter, a vertical positioning of the scrubbing unit is most desirable, but with such an arrangement it has been found that a cavitating action is induced in the fluid as an incident to the rotary movement of the brush unit, with the result that a tank of undue depth is required to prevent overflow of the fluid.

This cavitation also removes practically all of the fluid from the inner brush, and in some cases from the outer brushes and prevents proper rinsing of the glass surfaces as the dirt is scrubbed therefrom.

As a further defect in prior practice it is found that because the fluid moves with the brushes and at substantially the same speed, there is practically no rinsing or flushing action upon the brushes and hence the brushes require frequent cleaning or replacement.

In view of these difficulties, an important object of the present invention is to provide a new and improved method of and apparatus for washing glasses whereby turbulence is reduced and the normal cavitating action is overcome so as to reduce the depth of tank required, insure proper and continuous flushing of the brushes and the scrubbed surfaces of the glass, and eliminate the usual noise.

Prior devices have in most instances required a particular form and size of tank as well as a particular positioning in the tank, and it is a further object of the invention to provide a rotary glass washer constructed and arranged to operate with uniform efficiency independently of the size and shape of the tank and independently of its position in the tank.

Another object is to provide a glass washer of this character wherein exposed moving parts are eliminated so as to avoid the need for the usual guards, remove the customary danger to the operator, eliminate splashing, and reduce the breakage of glassware and machine parts.

A further object is to provide a light, compact and portable unit for washing glasses capable of easy installation and effective in such tanks which are relatively shallow.

Other objects and advantages will become apparent from the following description, taken in connection with the accompanying drawings, in which:

Fig. 1 is a side elevational view of a portable machine embodying the features of the invention, a portion of the device being shown in section to illustrate a part of the drive.

Fig. 2 is an enlarged vertical sectional view of the device taken along the line 2—2 of Fig. 1.

Fig. 3 is an enlarged horizontal sectional view taken along the line 3—3 of Fig. 1.

Fig. 4 is a vertical sectional view of an alternative embodiment of the invention adapted for permanent installation in a tank.

Fig. 5 is a plan view of a tank in which my improved machine is mounted, showing the direction and approximate rate of fluid movement for a given set of operating conditions.

In order to give a complete understanding of the principles of the invention, two forms of apparatus are herein illustrated and described, but it is to be understood that this disclosure is not intended as a limitation of the invention to this particular apparatus, it being contemplated that various changes might be made by those skilled in the art to adapt the invention to other types of apparatus without departing from the spirit and scope of the invention as defined by the appended claims.

For the purpose of imparting a thorough understanding of my invention and of facilitating the practice of my improved method of glass washing, I have in the appended drawings illustrated apparatus which embodies many desirable features of construction and operation apart from those necessary to attain the novel fluid motion required in said method, such apparatus being capable of embodiment in a compact portable machine such as that shown in Figs. 1 to 3, or in a similar permanently mounted machine such as that shown in Fig. 4.

The portable machine illustrated in Figs. 1 to 3 is one which is intended and particularly adapted for use in present wash tanks, such as the tank 10 of Fig. 2, and it is self-contained and unitary in construction in that it comprises a base 11 adapted to rest on the bottom 12 of the tank with a scrubbing means 13 supported on the base below the normal fluid level and an actuating motor 14 for said means carried above said level by a

standard 15 projecting upwardly from one end of the base.

To simplify the mounting and installation of the device, a plurality of suction cups 16 are preferably provided on the bottom of the base 11 to engage and attach to the bottom wall 12 of the tank and insure stable support for the machine.

As will be hereinafter explained in detail, the scrubbing means is rotary in character and to provide a rotary drive therefor, the motor 14 has an operating connection through the standard 15 and the base 11 which are both of hollow construction as shown in Figs. 1 and 2. A bracket 17 carried by the standard 15 provides the principal support for the motor 14, a conventional worm and worm wheel reduction gearing 14a being provided between the motor and a shaft 18 which extends downwardly through the standard. If desired, a coupling 19 may be provided in the shaft 18, the lower section of the shaft being fixed in a pinion 20 housed in the hollow base 11. The pinion 20 engages a relatively large gear 21 also housed in the base 11, the gear 21 being centered on the axis of the scrubbing means 13 and fixed to a shaft 22 which projects upwardly out of the base 11 through an upwardly protruding bearing 23 to support and rotate the scrubbing means 13.

As shown herein the scrubbing unit 13 comprises a central brush 24 of cylindrical form centered on the axis of the shaft 22, and two side brushes 25 positioned parallel to and on opposite sides of the central brush 24 with their bristles overlapping the bristles of the central brush in a radial direction as shown in Fig. 3. To support the brushes 24 and 25 a holder 26 is provided having a central collar 27 embracing the projecting upper end of the shaft 22 and having a driving connection therewith such as the bayonet slot arrangement 28. Into the upper end of the collar 27 the lower end of the central brush core 24a (Fig. 2) is fitted, and is secured by a screw 29.

To support the side brushes 25 oppositely projecting radial arms 30 are formed on the collar 27, the arms 30 at their outer ends having upwardly projecting parallel supports 31 carrying brush retainers 32 thereon. The retainers 32 are preferably in the form of T-slots into which the backs 25a (Fig. 3) of the side brushes may be dropped from above with the bristles projecting radially inwardly of the structure and their lower ends resting on the arms 30.

The present embodiment provides means for restraining the entrance of water into the base 11, and for this purpose a bell 35 is provided on the collar 27 so as to extend downwardly about the bearing 23 in closely spaced relation thereto. The arms 30 are joined to the lower edge of the bell 35. With this construction the rotary motion of the bell 35 and any water contained therein induces a centrifugal action which tends to draw the water from the bell downwardly and outwardly through the space between the bell and the bearing 23.

Because of the extreme danger of the rapidly rotating rigid parts of the scrubbing unit 13, the present invention provides stationary means which encloses and acts as a guard about these rigid parts. This means may, as in the present embodiment, also function as a means for directing and controlling the circulation of cleansing fluid as will hereinafter be described in detail.

Since this guard means is associated with rotating or circularly moving elements, it is preferably cylindrical in form and comprises a cylin-

drical housing 36 surrounding the scrubbing unit 13 and concentrically related thereto. The housing 36 is removably mounted by inserting its lower end in a seat provided by an upstanding flange 37 formed on the base 11 concentric with the shaft 22. The housing 36 is, of course, spaced slightly from the outer surfaces of the brush supports 31 so as not to interfere with the rotary motion thereof, and at its upper end an inwardly rolled flange 38 is provided which extends over the tops of the brush backs 25a and downwardly slightly along but spaced from their inner faces. Thus the rigid upper ends of the brush backs 25a and the supports 31 are fully guarded against contact with the operator or the glassware.

This protected relation of the rigid brush elements is one of the primary factors which contribute to the adaptability of the present device for portable construction, since it eliminates the usual need for separate guards. The necessity for such guards has, in the past, required the factory construction of the complete unit, including the washer and the associated guards. This requirement is, with the present construction, eliminated.

Proper utilization of the entire supply of cleansing fluid in the tank 10 of course requires circulation of such fluid through the brushes within the stationary housing 36. Normally the solution rises substantially to the level of the central brush tip, that is, above the upper edge of the housing 36 as shown in Fig. 2, and hence there is a constant tendency for fluid to run into the top of the housing. Provision is therefore made for the escape of fluid from the lower parts of the enclosure formed by the housing 36, the present embodiment having a plurality of openings 39 formed in the housing 36 slightly below the midpoint of the housing and at circumferentially spaced points thereabout.

When the scrubbing unit 13 rotates within the submerged housing 36, it acts as a pump impeller, imparting rapid rotation to the fluid with the incident centrifugal force which causes the fluid to flow outwardly from the housing through the openings 39. Thus, during rotation of the scrubbing unit, a constant circulation of fluid passes into the top of the housing, through the brushes, and out through the openings 39 as indicated by the arrows in Fig. 2. The volume of such circulation is, of course, governed by the speed of rotation of the unit 13, its frontal area, its clearance in the housing, the depth of fluid and the size of the openings 39, and may be varied as desired by variations in any one or more of these and possibly other controlling factors.

As hereinbefore pointed out, the present invention has for one of its primary objects the production of a device which, due to the elimination of appreciable cavitation, is capable of use in a relatively shallow tank. This end is attained by retarding and counteracting the natural swirling of the fluid, preferably through introduction of a counter-flow of fluid which tends to swirl in a direction opposite to the direction of rotation of the scrubbing unit 13.

In introducing such a counter-flow of fluid I prefer to utilize the impeller effect of the scrubbing unit and the resulting centrifugal discharge of fluid from the housing 36. This end is attained through controlling and directing the discharged fluid so as to prevent such fluid from continuing its swirling motion (in the direction induced by the unit 13) after it has left the hous-

ing 13. Best results are attained by actually deflecting such fluid in the opposite direction.

Thus, in the present instance, the openings 39 are in the form of louvres having sloping deflector or baffle surfaces 39^a which change the direction of swirling movement as shown by the arrows in Figs. 3 and 5.

The quantity of fluid thus discharged from the openings 39 is relatively small as compared with the total quantity of fluid in an ordinary tank, and hence the counter-swirling motion is relatively slow as compared with the rate of rotation of the scrubbing unit 13. This relative rate varies of course with the size of openings, depth of fluid, and the size and position of the unit therein.

An example is, however, illustrated in Fig. 5 of the drawings, indicating the rate of reverse rotation of the outer body of fluid to be approximately ten revolutions per minute when the scrubbing unit has a rate of two hundred fifty revolutions per minute.

With such a slow movement of the main body of fluid, practically a smooth level surface is obtained thereon as indicated by the line B in Figs. 2 and 4. This is in contrast to the usual surface, indicated at A, which obtains when the entire body of fluid rotates rapidly in the direction of brush rotation.

The surface contour A when the entire cavitating action takes place may, of course, vary with the size and shape of the tank so that in some cases it rises even higher about the side walls of the tank. The controlling effect of the counter-flow about the guard housing 36 prevents such elevation of the outer edges of the fluid and renders the present device operable in a tank the side walls of which are only slightly higher than the central brush tip.

Another operational feature of importance is the elimination of practically all noise due to the slow rate of movement of the major portion of the fluid bath.

In the operation of the device the cleansing fluid has a surface level about one inch above the top of the guard housing 36, making a total depth of about eight and one-quarter inches, the machine in the form of Figs. 1 and 2 having a total height to the top of the housing of seven and one-quarter inches. As the fluid is discharged from the housing 36 it is replaced by fluid dropping into the housing with a slight rotative movement counter to the direction of brush rotation, and such fluid is struck by the rapidly rotating brushes so that the fluid flushes through the bristles and thoroughly cleanses the brushes as an incident to the operation of the machine.

Due to the elimination of the large central cavity in the operation of the present device it is found that upon the insertion of a glass G into the machine, a relatively large quantity of cleansing solution is trapped in the glass so as to insure efficient scrubbing and rinsing of the inner surface.

In the embodiment illustrated in Fig. 4 of the drawings the device is constructed for permanent installation in a tank. This form, so far as the unit 13 and the guard 36 are concerned, is the same as that of Figs. 1 to 3, the difference being in the form of mounting and drive. The housing 36 is removably supported on a flat base 40 which rests upon the bottom wall of a tank 41 with the drive shaft 42 projecting from its central bearing through an opening 43 in the bottom of the tank.

Beneath the tank is a clamping plate 44, se-

cured by bolts 45 to the base 40, and carrying a bearing sleeve 46 for the shaft 42. Upon the lower end of the shaft is a pulley 47 through which the scrubbing unit may be driven from a suitable power source as in the embodiment of Figs. 1 to 3.

I claim as my invention:

1. The method of washing glasses and the like which consists in exposing a glass to the scrubbing action of rapidly rotating vertical brush 10 structure, and simultaneously directing a flow of cleansing fluid into said brush structure at the upper end thereof in a direction opposite to the direction of rotation of the brush structure.

2. The method of glass washing which consists in exposing a glass to the scrubbing action of a rapidly rotating brush structure, and simultaneously directing a flow of cleansing fluid into said brush structure at one end thereof in a direction tending to produce a swirling movement opposite to the direction of rotation of the brush structure.

3. A glass washing machine having a container for cleansing fluid, a scrubbing unit rotatably mounted on a substantially vertical axis in said container beneath the normal fluid level therein, means for rotating said scrubbing unit in one direction, and means operable to direct a swirling flow of fluid into one end of said scrubbing unit in a direction opposing the direction of rotation of said unit.

4. A machine of the character described having, in combination, a brush structure mounted for rotation about substantially a vertical axis, a stationary housing surrounding said structure and having openings in the sides thereof through which cleansing fluid may pass from said housing, a tank surrounding said housing in spaced relation thereto for containing cleansing solution, and means for rotating said brush structure.

5. A portable glass washing machine comprising, in combination, a base adapted to be positioned in a tank and to rest upon the bottom thereof, means on said base for securing the same in position on the bottom of the tank, a brush structure mounted on said base and upstanding therefrom for rotation about substantially a vertical axis, a standard mounted on said base at one side of said structure and rising from the base, a driving motor carried on said standard above the normal fluid level in such a tank, a driving connection driven from said motor and partially housed within said base for rotating said brush structure in one direction, and fluid deflecting means carried by said base in the path of the outward flow of fluid caused by rotation of said structure to reverse the direction of the swirling movement of such fluid as it moves outwardly away from said brush structure.

6. A portable device of the character described comprising, in combination, a hollow base adapted to be positioned in a tank and to rest upon the bottom thereof, a brush structure mounted on said base and upstanding therefrom for rotation about substantially a vertical axis, a housing surrounding said structure and having openings in the sides thereof providing for the escape of cleansing fluid from said housing, a standard mounted on said base at one side of said housing and rising from the base, a driving motor carried on said standard above the normal fluid level in such a tank, gearing driven from said motor and housed within said base for rotating said brush structure in one direction, and fluid deflecting means in the path of the flow of fluid from said

openings to produce a swirling movement of such fluid about the outside of said housing in a direction opposite to the direction of rotation of said brush structure.

5 7. A portable glass washing machine comprising a base adapted to rest within and upon the bottom of a tank, a stationary vertical housing mounted on said base and having an open upper end, a brushing means mounted within said housing for rotation about a substantially vertical axis, a standard upstanding from said base at one side of said housing, a driving motor carried upon said standard so as to be positioned above the normal fluid level in such a tank, a 10 driving connection between said motor and the lower end of said brushing means for rotating the same, said housing having openings for the lateral escape of fluid therefrom, and fluid deflecting means in fixed relation to said base and in the path of such escaping fluid for controlling 15 and directing the flow of such escaping fluid.

20 8. A portable glass washing machine comprising a base adapted to rest within and upon the bottom of a tank, a stationary vertical housing mounted on said base and having an open upper end, a brushing means mounted within said housing for rotation about a substantially vertical axis, a standard upstanding from said base at one side of said housing, a driving motor carried upon said standard so as to be positioned above the normal fluid level in such a tank, said 25 housing having openings through which fluid may be discharged from the housing, and a driving connection between said motor and the lower end of the brushing means for rotating the same.

30 9. A portable glass washing machine having, in combination, a hollow base adapted to be positioned in a tank and to rest upon the bottom thereof, a brush structure mounted on said base and upstanding therefrom for rotation about substantially a vertical axis, a housing surrounding said structure and having openings in the sides thereof through which cleansing fluid may 35 pass from said housing, a hollow standard mounted on said base at one side of said housing and rising from the base, a driving motor carried on said standard above the normal fluid level in such a tank, a driving shaft extending from said motor downwardly through said standard so as 40 to be housed thereby, gearing driven from said shaft and housed within said base for rotating said brush structure in one direction, and fluid deflecting means mounted in fixed relation to said base and in the path of the flow of fluid 45 from said openings to produce a swirling movement of such fluid about the outside of said housing in a direction opposite to the direction of rotation of said brush structure.

5 10. A glass washing machine comprising an upwardly opening stationary housing, a scrubbing unit rotatably mounted in said housing said unit having brushes thereon to engage and move about the surfaces of a glass or the like, said 10 housing having discharge openings therein, through which fluid may pass outwardly under the influence of centrifugal force, fluid deflecting means mounted in fixed relation to said housing in the path of such discharged fluid and operable 15 to direct such fluid with a swirling motion in one direction about said housing and means for rotating said scrubbing unit in the opposite direction to scrub the glass and impart rotating movement to the fluid within the housing in said 20 opposite direction.

25 11. A glass washing machine comprising, in combination, a rotary glass scrubbing unit, a housing enclosing said unit, said housing being apertured to permit the centrifugal discharge of fluid from the housing adjacent to one end thereof as the fluid is rotated by said scrubbing unit and to permit re-entry of fluid into said housing at the other end of the housing, and stationary fluid deflecting means located in the path of such flowing fluid and operable to direct and control the circulation of such discharged fluid as it flows from its point of discharge to its point of 30 re-entry.

35 12. In a washing device, the combination of a tank for containing washing fluid, scrubbing means mounted in said tank for rapid rotation about a substantially vertical axis, a housing surrounding said means through which fluid may flow longitudinally of said means from end to end and apertured to permit centrifugal discharge of fluid from the housing into the tank adjacent to one end of the housing and to permit re-entry of fluid from the tank into the housing adjacent to the other end of the housing, and a stationary fluid deflecting baffle means in said tank in the path of the flowing fluid and operable upon the fluid to reduce the rotative tendency of the fluid before it enters the said 40 other end of said housing.

45 13. A machine of the character described having, in combination, a tank for containing washing fluid, an elongated brush structure mounted in said tank for rotation about a substantially vertical axis, an elongated stationary housing in said tank and surrounding said structure and having openings therein through which fluid may enter and leave said housing and circulate throughout substantially the entire length of said housing while passing from its point of entry 50 to its point of leaving said housing, and means for rotating said brush structure.

VINCENT W. CUNNINGHAM.
